UNITED STATES PATENT OFFICE.

JOSEPH H. BENNETT, OF NEW YORK, N. Y.

GAS-STOVE.

No. 904,243.

Specification of Letters Patent.

Patented Nov. 17, 1908.

Application filed January 22, 1908. Serial No. 412,063.

To all whom it may concern:

Be it known that I, JOSEPH H. BENNETT, a citizen of the United States, residing at New York city, in the county of New York 5 and State of New York, have invented certain new and useful Improvements in Gas-Stoves, of which the following is a specification.

My invention relates to improvements in 10 gas stoves, and the object of my invention is to provide a simple and convenient device for heating by gas flame.

My invention is illustrated in the accompanying drawings in which 15 Figure 1 is a vertical section of the device. Fig. 2 is a view of the burners and chamber removed from the casing, Fig. 3 is a view from above of one half of a burner, Fig. 4 is a vertical cross section of a burner.

20 Similar numerals refer to similar parts throughout the several views.

Air is admitted to the stove by means of the duct 1, while gas is admitted through the pipes 2 and 3. The gas in the pipe 2 is discharged into chamber 5, from which the upwardly extended pipes 6, 7, 8, 9, and 10 25 convey the gas to certain of the burners 20. The burners 20 are screwed into the upper plate 24 and receive respectively the upper 30 ends of the pipes, 6, 7, 8, 9, and 10. Nipples or burners of any desired form may be employed, but I prefer to use the form shown in the drawings, in which the upper end section is contracted, and is provided with four 35 interiorly projecting lugs 22, by means of which the said pipes are held in position.

The gas admitted through the pipe 3 is discharged into the chamber 4, and from it is discharged at other of the nipples or burners 20, through the pipes 11, 12, 13, and 40 14 in the same manner as described above.

My device assembled as above set forth is inclosed in a casing 15, which is preferably made of cast or sheet iron. At the section of 45 the casing which surrounds the burners, I preferably provide a non-conducting sheath-

ing 17 of fire brick or other suitable material, which may be supported by angle pieces 16 secured to the casing 15 by means of rivets or in any other suitable manner. 50

A cover 18 which may be made in sections in the usual manner is secured to the upper edge of the casing 15 by means of rivets 19 or in any other desired manner.

In operation, the gas admitted through the 55 pipes 2 and 3 is discharged through the pipes 6 to 14 at the burners 20. At the upper end of the pipes the air, admitted through the duct 1, is mixed with gas and combustion takes place in the usual manner, the air passing 60 through the passages between the lugs 22. If desired the air may be expelled by forced draft.

When it is desired to use less than the full 65 number of burners, the supply of gas through the pipe 2 may be shut off by means of cock 26, or the gas from the pipe 3 may be shut off by means of the cock 25.

Having thus described my invention what 70 I claim is.

The combination of two gas chambers, each provided with a plurality of upwardly extending pipes, independent ducts for supplying gas to said gas chambers, a shut-off valve in each of said ducts, an air chamber 75 having a plurality of outlet apertures in its upper side, burner tip members seated in said apertures in the air chamber, and each consisting of a hollow nipple, provided with a circumferential wrench hold section, and being externally screw threaded below said wrench hold section, and provided with a contracted neck section having interiorly projecting lugs therein, and pipes extending upwardly from the gas chamber and engaging 80 said lugs.

In testimony whereof I have affixed my signature in presence of two witnesses.

JOSEPH H. BENNETT.

Witnesses:

WILLIAM LYMAN,
GEORGE M. FOULDS.
